UNITED STATES PATENT OFFICE.

A. M. CONNETT, OF MADISON, INDIANA, ASSIGNOR TO J. C. MOORE AND SARAH A. CONNETT, OF SAME PLACE.

IMPROVEMENT IN SHINGLE-MACHINES.

Specification forming part of Letters Patent No. 58,938, dated October 16, 1866.

To all whom it may concern:

Be it known that I, A. M. CONNETT, of Madison, in the county of Jefferson and State of Indiana, have invented new and useful Improvements in Shingle-Machines; and I do hereby declare that the following is a full, clear, and exact description thereof, which will enable others skilled in the art to make and use the same, reference being had to the accompanying drawings, forming part of this specification.

The object of the present invention is to rive and shave shingles directly from the bolt or block, the shaving being done in such manner that the portions of the shingles exposed to the weather when placed upon the roof of a building or other place will be of uniform thickness, and not cut across the grain, as in shingles shaved with a gradual taper from butt to point.

In the accompanying plate of drawings my improvements in shingle-machines are illustrated, Figure 1 being a plan or top view of the machine; Fig. 2, a central longitudinal vertical section taken in the plane of the line $x\ x$, Fig. 1; Fig. 3, a transverse vertical section taken in the plane of the line $y\ y$, Fig. 2; and Fig. 4, an elevation of a portion of one side of the machine.

Similar letters of reference indicate like parts.

A in the drawings represents the main supporting-frame of the machine; B, the driving-shaft, hung in suitable bearings of one end of the frame A, across which it extends. A crank-handle is secured to one end of shaft B, for turning the same; and D is a pinion-wheel on same end of shaft, meshing into a gear-wheel, E, placed above it, and secured to a horizontal shaft, F, extending across the machine, and turning in suitable bearings of its frame A. On the opposite end of the shaft F is secured a crank-arm, G, to the outer end of which is hung a pitman-rod, H, connecting it with a cross-head or block, I, arranged to slide in suitable ways or guides J of one end, K, of the machine. To the upper side of the sliding head or block a splitter, L, is secured by bolts, or in any other proper manner, so as to be susceptible of detachment and attachment at pleasure, which splitter projects, by its cut-

ting and beveled end M, beyond the head or block toward the end of the machine at which the driving-shaft is arranged, as before explained.

N is a hopper or box secured to the upper side of frame A, and at an intermediate point, or nearly so, between the two ends of the same, into which hopper the block or bolt from which the shingle is to be split is placed, resting at its lower end upon the bottom plate, O, of the hopper, and against the edge of the transverse horizontal knife-blade P, secured at the lower portion of the front end, Q, of the hopper to the main frame, and below which knife-edge the hopper is open across its width. B is a bent spring secured in the bottom of the hopper, and arranged to bear upon the side of the block placed therein. The end S of the hopper toward the splitter is open at its lower portion, so as to allow the splitter to pass into it and through its entire length as it moves forward by the action of the crank and pitman-rod, connecting the head to which the splitter is attached to the driving-shaft, the width of the splitter-blade corresponding to that of the inside of the hopper.

The block or bolt from which the shingles are to be split is put in the hopper N, and brought to bear against the knife-blade P, secured in its front end, with the spring R pressing against its side, when, the driving-shaft being turned in the proper direction to move the splitter-blade forward or toward the hopper O, it is brought to bear upon the block therein, and, first forcing the same firmly against the knife-edge I, thus partially indenting or marking the block across its width, it then, by continuing its forward motion, splits the same, when the projecting piece T, placed under the splitter, (where it is secured in the sliding head-block so as to be susceptible of adjustment therein by means of a set or thumb screw, U,) then strikes against the split-off portion of the block resting upon the bottom plate of the hopper, driving it under the knife-blade, to and between revolving feed-pressure rollers V V, placed one above the other, (the lower one turning in fixed bearings, and the upper in adjustable bearings,) by which rollers the said split portion is then carried along to and between another set of feed or pressure

rollers, W W, similarly arranged and hung in the frame A to that of the rollers V, when, having passed between the last set of rollers, it then escapes from the machine; the said split portion of the block, however, as it passes from the first set of feed or pressure rollers to the last set, being acted upon by a series of knife-blades, the relative arrangement of which will be now explained, as well as the purpose and object of their use.

X is a knife-blade, extending across the machine, and placed therein a little to one side of the lower feed-roller of the first set in a horizontal plane, and in position for acting upon, and thus to shave or smooth, the under side of the split portion of the block passing between the feed-rollers V, the upper side of the said split portion of the block being acted upon and shaved by a transverse horizontal knife-blade, Y, secured at each end in the upper ends of a sliding frame, Z, arranged to move up and down in a vertical plane between the two sides of the main frame A. The space or distance between the two knife-blades X and Y is equal to the extreme thickness which the butt of the shingle is to have, which distance, in order to produce the desired taper from the butt to the point of the shingle, is gradually and regularly decreased by the depression of the frame Z, carrying the upper knife, Y, through the action of the revolving eccentric or cam A², secured to the transverse horizontal shaft F, hereinbefore referred to, upon the lower cross-bar, C², of such frame, when, this cam or eccentric having ceased to act upon the cross-bar C², the frame is then thrown up or back to its original position by means of the fixed bent spring D², upon which it rests at its lower end.

From the above it is plain to be understood that if the cam or eccentric A² is made of proper shape therefor the depression of the vertical frame Z, carrying the knife-blade, may be made to commence at any desired point of the length of the split-off portion of the block passing through the feed-rollers, whereby, as is obvious, one of the objects of the present invention, as hereinbefore stated, (which is to have the butt or that portion of the shingle that is exposed to the action of the weather of an even thickness throughout its entire length,) can be accomplished, the said cam also being made of suitable shape to allow the knife-frame Z

to rise when the knife has reached the point of the shingle.

While the shingle is shaved upon the upper and lower sides and tapered upon the upper, one of its sides or edges is acted upon and shaved by the jointing knife-blade E², fixed to one side of the machine and opposite to that at which the bent spring R bears against the block in the hopper, while against the other side of the shingle a jointing knife-blade, F², acts, which knife-blade is arranged upon a screw-shaft, G², extending transversely across the machine, and turning in bearings of the same, so that it can be adjusted to any width of shingle which may be running or passing through the machine.

From the above description it is obvious that when the split-off portion of the block carried through the feed-rollers W W escapes from the machine it is a perfect shingle in every respect, and fit to be used.

The feed-rollers are rotated at a uniform velocity through suitable gearing connecting the two of each set together and to the gear-shaft F, the peripheries of the two rollers constituting the first set being toothed or serrated, so as to obtain a more firm and reliable hold upon the shingle as it passes between them, and thus more rigidly hold it to the action of the various knives used, while the peripheries of the last or second set are smooth.

Having thus described my invention, I claim as new and desire to secure by Letters Patent—

1. Splitting, shaving, tapering, and jointing a shingle by one operation by means of a splitter-knife, L, lower stationary knife-blade, X, upper movable knife-blade, Y, and side knife-blades or chisels, E² and F², in combination with suitable feed-rollers, when they are all arranged together so as to operate and to be operated substantially in the manner described.

2. The stationary knife-blade P, in combination with the splitter-blade I, substantially as and for the purpose specified.

3. The adjustable piece T, secured to the under side of the splitter-blade, substantially as described, for the purpose specified.

A. M. CONNETT.
